UNITED STATES PATENT OFFICE.

TIMOTHY SEARY THORN, OF PLAINFIELD, NEW JERSEY.

KEY-HOLDER FOR LOCKS.

SPECIFICATION forming part of Letters Patent No. 670,626, dated March 26, 1901.

Application filed November 22, 1900. Serial No. 37,380. (No model.)

To all whom it may concern:

Be it known that I, TIMOTHY SEARY THORN, a citizen of the United States, residing at Plainfield, in the county of Union and State 5 of New Jersey, have invented a new and useful Key-Holder for Door-Locks, of which the following is a specification.

The invention relates to improvements in key-holders for locks.

One object of the present invention is to improve the construction of key-holders for locks and to provide a simple, inexpensive, and efficient device adapted to be readily applied to locks and capable of holding a key 15 out of alignment with the keyhole to prevent it from being jarred out of the door or taken out by small children, so that the key will not become lost.

Another object of the invention is to provide a device of this character adapted to allow sufficient free movement of the key to operate the lock-bolt and capable of permitting the key to readily pass it when the necessary pressure is applied.

The invention consists in the construction and novel combination and arrangement of parts hereinafter fully described, illustrated in the accompanying drawings, and pointed out in the claims hereto appended.

In the drawings, Figure 1 is an elevation of a lock, the removable plate or face being detached to show the key-holder. Fig. 2 is a sectional view of the same. Fig. 3 is a detail perspective view of the resilient holder or spring. Fig. 4 is a similar view of the post for supporting one of the ends of the spring. Fig. 5 is a detail view illustrating a slight modification of the invention.

Like numerals of reference designate corresponding parts in all the figures of the drawings.

1 designates an approximately V-shaped spring, designed to be arranged within a lock-casing 2 to form a resilient key-holder to be 45 engaged by a key 3 to prevent the same from swinging to a position in alignment with the keyhole 4 of the casing, whereby the key will be effectually prevented from being jarred out of the door or removed by small children.

The key-holder, which is adapted to prevent a key from becoming lost, is composed of inclined upwardly-diverging sides 5 and a short

connecting portion 6, which rests against the bottom of the lock-casing and which extends preferably beyond each side of the keyhole, 55 as clearly shown in Figs. 1 and 5. The sides of the spring or resilient holder are straight and are supported by posts 8 and 9, which may be arranged as illustrated in Fig. 1 of the accompanying drawings or as shown in 60 Fig. 5. The sides 5 of the key-holder are arranged to be flexed by the key in turning the same to carry its bolt-engaging portion upward to operate the bolt, as the distance between the enlarged portion of the keyhole 65 and the sides of the spring is less than the length of the engaging portion of the key.

The key-holder is designed to be made of a sufficient strength to resist the efforts of young children to turn the key; but the latter 70 may be readily moved past the spring when the necessary pressure is applied.

The post 8, which is arranged at the left-hand side of the spring in Fig. 1 of the drawings, is provided with an approximately V- 75 shaped recess 10 to receive the adjacent end of the spring, and the other end of the spring is arranged in a recess formed by the post 9 and the adjacent wall of the lock-casing.

In Fig. 5 of the accompanying drawings 80 the post 11, which supports the bolt, is utilized for holding the spring or holder, and a supplemental post 12 is arranged adjacent to the post 11 to form the tapering or V-shaped recess for the reception of the spring or holder. 85 The other end of the spring is arranged within a recess formed by a post 9^a and the adjacent wall of the casing. The post 9^a is constructed like the post 9, heretofore described. The spring is firmly held in proper position 90 by the posts and the casing of the lock, and it will effectually prevent a key from being accidentally lost out of a door.

It will be seen that the key-holder is exceedingly simple and inexpensive in construction, that it is adapted to be readily applied to a lock and is not liable to become broken or to get out of order, and that it is capable of effectually preventing a key from being jarred out of the door or taken therefrom by 100 young children. It will also be apparent that the post 8, which supports the left-hand side of the key-holder in Fig. 1 of the accompanying drawings, performs a double function in

that it is recessed to receive the adjacent end of the holder and is located at the lower edge of the bolt and is adapted to support the same and limit the movement thereof.

5 The posts for supporting the ends of the holder are designed to be cast integral with the lock-casing, but they may be formed in any other manner, and I desire it to be understood that various changes within the 10 scope of the appended claims may be resorted to without departing from the spirit or sacrificing any of the advantages of this invention.

What I claim is—

15 1. The combination with a lock, of a resilient key-holder arranged within the lock and provided with sides located at opposite sides of the keyhole and extending upward from the bottom of the latter and arranged to receive a key between them to limit the movement of the key and adapted to be flexed by the same, substantially as described.

20 2. The combination with a lock, of an approximately V-shaped spring forming a key-holder and composed of diverging sides located at opposite sides of the keyhole and extending upward from the bottom of the latter and receiving a key between them, and a

straight connecting portion arranged at the bottom of the keyhole, and post supporting 30 the spring, substantially as described.

3. The combination with a lock, of an approximately V-shaped spring forming a resilient key-holder and arranged at the keyhole of the casing in position to receive a key 35 between its sides, and the posts supporting the ends of the spring, one of the posts being provided with a tapering recess, substantially as described.

4. The combination with a lock having a 40 sliding bolt, of an approximately V-shaped spring forming a resilient key-holder and arranged at the keyhole in position to receive the key between its sides, the post 8 supporting the bolt of the lock and provided with 45 a recess receiving the adjacent end of the key-holder, and means for supporting the other end of the holder, substantially as described.

In testimony that I claim the foregoing as my own I have hereto affixed my signature in 50 the presence of two witnesses.

TIMOTHY SEARY THORN.
